(57) **CLAIM**

The ornamental design for cable connector having interchangeable color bands, as shown and described.

DESCRIPTION

FIG. 1 is an elevational view of a cable connector having interchangeable color bands showing my new design;

FIG. 2 illustrates the color band shown in FIG. 1, partially in elevation view in lower half, and sectional view in upper top.

FIG. 3 is a rear view of the color band shown in FIG. 2;

FIG. 4 is an end elevation view thereof; and,

FIG. 5 is another end elevation view thereof.

The stippled portions shown in FIGS. 1, 2 and 3 represent different selected colors.

The broken line showing of the environment in FIGS. 1, 4 and 5 is for illustrative purposes only and forms no part of the claimed design.
